FURNACE REGULATOR

John E. Haines, Chicago, Ill., assignor to Minneapolis-Honeywell Regulator Company, Minneapolis, Minn., a corporation of Delaware

Application August 19, 1938, Serial No. 225,825

1 Claim. (Cl. 236—9)

My invention relates to temperature regulators and is more particularly applicable to control of coal fired furnaces and boilers by automatic regulation of the draft and check dampers normally forming part of such equipment.

The object of my invention is to provide a compact, efficient, and inexpensive temperature regulator adapted for controlling the draft through coal fired heaters.

Another object is to provide a device of this general nature which dispenses with cumbersome weights and similar arrangements and utilizes adjustable resilient devices for securing automatic control of a furnace or boiler.

Another object is the provision of a damper regulator for controlling a coal fired heater which is adjustable by a space thermostat for maintaining a relatively high heater temperature when the thermostat is calling for heat and for maintaining a relatively low heater temperature when the space thermostat is satisfied, thereby preventing the fire from going out during such periods.

Another object is the provision of a spring loaded temperature regulator responsive to heater conditions having space temperature responsive mechanism for adjusting the spring loading.

Another object is the provision in a device of the character described of independent high and low limit temperature adjustments.

Other objects and advantages of my invention will become apparent from the detailed specification following, the invention residing in the improved construction, arrangement, and combination of parts.

The single figure of the drawing is a cross-sectional view of a preferred form of my invention installed in a furnace damper control system.

Referring to the drawing, I have shown my improved regulator generally at 1 as comprising a substantially cylindrical casing 2 having a bottom plate 3 suitably secured thereto by means of screws or the like 4. Formed integrally with the bottom plate 3 is a nipple portion 5 which may be engaged in screw-threaded relation with a suitable fitting in the upper part of a boiler. Engaged in screw-threaded relationship with the interior of the nipple portion 5 is a fitting 6 to which is secured the lower of a plurality of expansible cells 7. The expansible cells 7 are comprised of diaphragm members sealed together so as to be fluid tight, the cells communicating with each other and with a sealed tube 8 extending downwardly from the fitting 6 within the nipple 55

portion 5. The cells 7 and tube 8 may be filled with a temperature responsive medium and collectively form a heat responsive element in the manner well known in the art. Supported on the upper surface of the uppermost of the cells 7 is a plate or disc 11 which may be suitably fastened to the expansible cells and which has integrally formed therewith a lug 12 to which is pivoted a lever 13 by means of a pivot pin 14. The lever 13 extends through an opening 15 in one side wall of the casing 2 and through an opening 16 in the opposite side wall and is pivoted at 16 to a fixed support 17 extending integrally from the side wall of the casing 2.

Numeral 20 designates generally a heat motor which is disposed in the upper part of the casing 2 and comprises a pair of expansible cells 21 and 22. The cells 21 and 22 are each formed of diaphragms suitably secured together at their edges so as to be fluid tight and are also filled with a temperature responsive medium adapted to expand upon the application of heat thereto. The upper diaphragm of the cell 21 has a central embossment or convex portion 23 which engages and interfits with a corresponding depression in the top of the casing 2 for the purpose of retaining the cell 21 in position. The lower diaphragm of the cell 22 has a similar embossment or convex portion 24 which engages and interfits with a corresponding depression formed in a disc or plate 25 bearing against the bottom of cell 22. Interposed between the cells 21 and 22 is a grid or framework 26 comprising plates 27 and 28 which bear against the cells 21 and 22, respectively, and are held in spaced relation by spacing members 29 and 30. Supported by the spacing members 29 and 30 is a heat resistant element 31 upon which is wound a coil 32 of electrical resistance wire forming a heater. The ends of the resistance wire 32 are connected to a pair of electrical conductors 33 and 34.

Integrally formed on the plate 25 is a projecting portion 37 which engages in a suitable depression in the end of a lever 40. The lever 40 is pivoted at 41 to the support 17 and also extends through the opening 15 in the side wall of the casing 2. Connected between the left ends of the levers 13 and 40 is a coil spring 42, the upper end of which engages a member 43 engaged on a screw 44 extending through the end of the lever 40 and locked in position by means of a lock nut 45. Clockwise movement of the lever 40 about its pivot is limited by a screw 46 extending through a bracket 47 formed integral-

ly with the casing 2, the screw 46 being locked in position by means of a lock nut 48.

As previously pointed out, my improved regulator is primarily adapted for controlling the dampers of a coal fired furnace or boiler. In the system which I have shown, numeral 50 designates a boiler which may be of conventional type having a draft damper 51 and a check damper 52 in the smoke pipe of the boiler. As previously described, the regulator 1 is mounted on the boiler by having the nipple portion 5 screwed into a suitable fitting in the top of the boiler with the tube 8 extending into the boiler water. Numeral 53 indicates a flexible connection, preferably a chain, one end of which is connected to the draft damper 51 and the other end of which is connected to the check damper 52. The right end of the lever 13 is also connected to the chain 53 and the chain may be passed over pulleys 54, 55, 56, and 57 mounted in pulley blocks suitably disposed with respect to the installation so that the chain can be easily moved for operating the dampers.

The device may be controlled from a space or room thermostat 60 which may preferably be of a conventional type comprising a bimetal element 61 arranged to actuate a movable switch arm 62 cooperating with a fixed electrical contact 63. The electrical conductor 33 previously described is connected to the fixed electrical contact 63 and the conductor 34 may lead to a suitable source of external power, not shown. Another electrical conductor 64 also leading to the external source of power is connected to the thermostat 60.

With the parts in the position shown, the room or space thermostat 60 is calling for heat and a circuit energising the electrical heating resistance 32 is completed through the conductor 64, the thermostat, conductor 33, resistance 32, and conductor 34. Heat from the resistance 32 has caused expansion of the fluid contained in cells 21 and 22 causing the lever 40 to be moved in a clockwise direction until it has engaged the stop screw 46. As can be seen from the drawing, this clockwise movement of lever 40 has added a certain amount of tension to the spring 42, which has caused movement of lever 13 in a clockwise direction so as to move the chain 53 in a direction to open the draft damper 51 as shown and close the check damper 52. By reason of these positions of the dampers, the rate of combustion will be increased in the furnace for supplying heat to the spaces wherein the thermostat 60 is located. As the boiler temperature increases above the desired value the fluid within the cells 1 will expand correspondingly, tending to move the lever 13 in a counterclockwise direction against the force of spring 42. This will cause movement of the draft damper towards closed position and the check damper towards open position for reducing the rate of combustion. Conversely, upon a decrease in boiler temperature, the cells 1 will contract under the action of spring 42, which will cause the dampers to be shifted in a direction to increase the rate of combustion. In this manner, the regulator will act to maintain the boiler water at the desired temperature. The temperature maintained in the boiler when the room thermostat is calling for heat may be conveniently adjusted by adjusting the position of the screw 46 in the bracket 47. By unscrewing the screw 46, the heat motor 20 will cause lever 40 to be moved further in a clockwise direction tending to increase the tension of spring 42 which raises the

temperature setting of the regulator. Conversely, by screwing down on screw 46, the tension on spring 42 due to expansion of the heat motor is decreased which lowers the temperature setting.

Should now the thermostat 60 become satisfied indicating that no further heating is necessary for the time being, the heater 32 will be de-energized causing the cells comprising the heat motor 20 to collapse. This will immediately permit lever 40 to rotate in a counter-clockwise direction, releasing some of the tension in spring 42 which will cause lever 13 to be rotated in a counter-clockwise direction so as to close the draft damper 51 and open the check 52. By reason of the positions the dampers are now in, the furnace fire will diminish and the pressure within the cells 1 will drop accordingly. When the boiler temperature has dropped to some low value, which may be for example 100°, it is desirable that the dampers be open slightly in order to prevent the fire from becoming completely extinguished. When the pressure within the cells 1 of my device has dropped to a value corresponding to such a temperature of the boiler, the lever 13 will have been moved clockwise under the combined action of the spring 42 and cells 1 to slightly open the draft damper 51 and to move the check damper 52 to closed position. The boiler responsive device comprising the cells 1 will now control the temperature of the boiler and maintain it substantially at 100° in this manner, or at some other suitable value which may be determined by adjustment of the screw 44. In order to adjust the low limit of boiler temperature to be maintained, for example, to lower it, the screw 44 may be unscrewed tending to reduce the amount of tension in the spring 42. Obviously, the result will be that the pressure in the cells 1 will have to fall to a lower value before it will be unbalanced by the reduced amount of tension in the spring 42 so as to cause the lever 13 to be moved in a direction to open the draft damper 51 and close the check 52.

From the foregoing, it is apparent that I have provided a compact and sturdily constructed device for controlling the temperature of a furnace wholly automatically in a manner such that overheating is prevented and additionally the fire is prevented from becoming extinguished. The boiler responsive device controls the boiler temperature and prevents it from exceeding a limiting relatively high value when the space thermostat is calling for heat and controls the boiler temperature maintaining it at a relatively low value when the space thermostat is not calling for heat. This is accomplished as I have described by automatically changing the adjustment, or in other words, the loading of the spring 42. A further advantage of my invention is that I have provided separate adjustments as I have described for adjusting the high and low limit temperatures of the boiler which are to be maintained. This provides an important convenience inasmuch as in different installations wherein this type of boiler is used or where different temperatures are desired to be maintained the requisite adjustments may be easily made by the arrangements which I have provided.

In referring to furnaces and boilers in the foregoing description, as generally understood in the art a furnace supplies warm air and a boiler supplies hot water or steam, my invention being equally applicable to both.

In accordance with the patent statutes, I have

disclosed and described in detail a representative preferred form of my invention. There are other forms and embodiments which my invention may take and many changes and variations will occur to those skilled in the art but which are within the scope of my invention as manifested in the representative form herein disclosed. The boundaries of my invention are, therefore, to be determined only by the scope of the appended claim.

I claim as my invention:

In a damper regulator system for operating a combustion regulating damper for a solid fuel fired space heater, in combination, a base member, a first diaphragm means carried on said base member and responsive to a pressure varying with the temperature of the heater, means pivoted on said base member and actuated by said first diaphragm means for positioning said damper, biasing means including a spring for 20

5 biasing said pivoted damper actuating means toward heat increasing position, adjusting means including a lever having a pivot on said base member for adjusting said biasing means to determine the temperature maintained by the heater, a second diaphragm means carried on said base member for actuating said adjusting means and responsive to a pressure varying with a second temperature varying with a demand for 10 heat, an adjustable stop means supported on said base member and adapted to engage said lever to limit the maximum temperature of said heater upon heat demand from said second temperature responsive means, and separate means for adjusting said biasing means so as to maintain a predetermined low heater temperature when said second temperature is satisfied for thereby causing the regulator to maintain the fire slightly active at such times.
